UNITED STATES PATENT OFFICE.

NICHOLAS J. SHERRILL, OF CHARLOTTE, NORTH CAROLINA.

CRATE-TILTING DEVICE.

No. 843,708.

Specification of Letters Patent.

Patented Feb. 12, 1907.

Application filed April 2, 1906. Serial No. 309,525.

To all whom it may concern:

Be it known that I, NICHOLAS J. SHERRILL, a citizen of the United States, residing at Charlotte, in the county of Mecklenburg and State of North Carolina, have invented certain new and useful Improvements in Crate-Tilting Devices, of which the following is a specification, reference being had therein to the accompanying drawings.

This invention relates to new and useful improvements in tilting stands or racks for holding receptacles for facilitating the dispensing of liquids therefrom, and comprises means whereby the standard on which the device is pivotally held may be adjusted to securely clamp the sides of the crate or case holding the receptacle and forming a protection to the bottom and sides thereof.

My invention comprises various other details of construction and combinations and arrangements of parts, which will be herein-after fully described and then specifically defined in the appended claim.

I illustrate my invention in the accompanying drawings, which, with the letters of reference marked thereon, form a part of this application, and in which—

Figure 1 is a perspective view of my invention, showing the standard upon which the receptacle-holder is mounted as closed in or adjusted to thoroughly brace the holder. Fig. 2 is a similar view showing the receptacle-holder pivotally mounted upon the standard. Fig. 3 is a side elevation showing the holder tilted, and Fig. 4 is a detail perspective view of the upper end of one of the standards.

Reference now being had to the details of the drawings by letter, A designates a holder for a receptacle, which may be of any suitable material and size or shape, and fixed to the opposite sides of the holder are two metallic plates B, each having a longitudinal groove B' therein, which groove is preferably centrally disposed, and C designate apertures formed in said plates.

D designates a standard having two inclined legs D', the upper ends of which come together and are parallel to each other and bent at an angle, as at E, each pair forming a horizontal pivot F, designed to engage one

or the other of the apertures C, which are formed in said plates. Said legs D' are preferably resilient and may be sprung laterally for the purpose of disengaging the same from the apertures in the plates B when it is desired to raise or lower the receptacle-holder to allow the same to tilt or to be closed down in the manner shown in Fig. 1 of the drawings. Said parallel portions of the standard are adapted to bear against said ribs to normally hold the crate from tilting.

It will be noted that when the crate is lowered in the position shown in Fig. 1 the pivots F engage the upper of the apertures in said plates B, and the bottom of the holder rests upon the transverse portions of the shoulders D, while the inclined legs bear frictionally against the opposite sides of the holder, thus securely bracing the crate or holder.

By the provision of the apparatus shown and described it will be noted that a simple and efficient means is afforded for thoroughly bracing the holder while in transit or at other times by the peculiar manner of the engagement of the standard with the crate or holder, while the apparatus may be easily and quickly adjusted so that the crate, which is adapted to hold a receptacle from which liquid is to be dispensed, may be tilted back and forth.

What I claim is—

A tilting receptacle-holder comprising a crate, plates secured to two of the outer faces upon opposite sides of the crate, each plate provided with projecting ribs upon its outer face and each plate being apertured between said ribs, a standard comprising bail-shaped wires, the upper ends of which are fastened together and bent at right angles and adapted to engage said apertures in said plates, parallel portions of the standard which are held together being adapted to bear against said ribs to normally hold the crate from tilting, as set forth.

In testimony whereof I hereunto affix my signature in presence of two witnesses.

NICHOLAS J. SHERRILL.
